VERGILIO BIASIZZO, OF BINGEN, GERMANY.

RAILWAY SIGNALING DEVICE.

Application filed July 31, 1926. Serial No. 126,223.

This invention relates to a railway signaling device, and its object is to provide improved means on the locomotive of a train and on the permanent line respectively, by 5 which it is indicated by an audible signal when the line is blocked, for the purpose of preventing railway accidents.

The accompanying drawing illustrates the improved device: Fig. 1 is a side view of part 10 of a locomotive on a permanent line, with the device partly in section; Fig. 2 is a front view, and Fig. 3 is a perspective view of part of the device.

The device comprises a rectangular 15 bracket *a* fixed with its vertical member to the locomotive frame, preferably to the lower end of the front wall *b* of the conductor's stand, by means of rivets *c*. The horizontal member of said bracket carries a depending 20 spring casing *d*, of which the lower end is closed by a screwed cover *e* while the upper end is open. Said casing serves for the reception of a strong draw-spring *f* therein, which at its lower end is attached to the 25 cover *e* while its upper end is fixed to a movable disc *g* located in the spring casing and having two laterally projecting pins *h* by which it is guided in vertical slots *i* of the 30 spring casing *d*. The spring *f* is by the same lateral pins *h* suspended in its highly stretched position from rearwardly directed 35 catches *l* of a forked arm *k*, which is pivoted to a lug *m* on the vertical member of the bracket *a* and below said lug connected with 40 said member by means of a spring *n* that tends to pull the arm *k* constantly toward said member. Laterally of the bracket *a* and the spring casing *d* a double-armed lever *o* is pivoted at *p* to the locomotive frame, 45 the upper arm of said lever being in slot-and-pin connection *q*, *r* with the forked arm *k*. The upper surface of the movable disc *g* is fitted with two eyes *s* to which wire cords *t*, *u* are fixed. One of said cords, *u*, is guided 50 over a roller *v* and led into the conductor's stand, whence it can be pulled upwards for stretching or tensioning the draw-spring *f* and creating the engagement between the lateral pins *h* and the forked arm *k*, the latter being for this purpose provided at its 55 lower extremities with an incline *w* along

which the pins *h* travel upwards until they engage in catches *l* of the forked arm *k*. The other cord *t* is so connected with a valve lever *x* of the steam pipe on the locomotive 55 that the latter sounds when the cord *x* is pulled downwards. The lower arm of the lever *o* is so arranged that an abutment plate *z* hinged to a block *y* on the permanent line and adapted, when the line is blocked, to 60 be pulled into its erected position shown in Fig. 1 by any appropriate means, lies within the path of said lower lever arm.

As soon as the lever *o* strikes against the 65 erected plate *z*, the forked arm *k* is pushed forward against the action of the spring *n* in such a way that the pins *h* become disengaged therefrom so that the spring *f* is freed and allowed to jump downwards 70 whereby the cord *t* is pulled and the steam pipe on the locomotive is actuated.

As already explained, the device can be returned to its operative position by pulling the cord *u* from the conductor's stand, the 75 valve lever *x* returning automatically to its closing position by means of a spring *x*¹ acting thereon, whereby the steam pipe ceases to sound.

What I claim, is:—

A railway signaling device, comprising a 80 fixed rectangular bracket on a locomotive, a spring casing having lateral vertical slots and a closed lower end and depending from said bracket, a draw-spring arranged in said casing and at its lower end attached to the closed lower end thereof, a movable disc in 85 said casing to which the upper end of said spring is attached, laterally projecting pins on said movable disc guided in the slots of said casing, a forked arm pivoted to said bracket and having a spring connection therewith tending to pull the arm constantly toward the bracket rearwardly directed catches on said forked arm adapted to engage with said pins when the spring is in its tensioned position, an incline at the lower extremities of said forked arm, two wire cords attached to the upper surface of said disc of which one led into the conductor's 95 stand of the locomotive serves for pulling said draw-spring into its tensioned position and the pins on said disc into engagement 100

with said forked arm while the other cord is connected with the steam valve on the locomotive, a double-armed lever fulcrumed on the locomotive and at its upper arm in 5 slot-and-pin connection with said forked arm, and a hinged abutment plate on the permanent railway line adapted to be pulled

into its erected position when the line is blocked and then lying within the path of the lower arm of said lever, substantially 10 as and for the purpose set forth.

In testimony whereof I have hereunto set my hand.

JAKOB MÜLLER.
